UNITED STATES PATENT OFFICE.

JOHN SCHEMINGER, JR., OF PROVIDENCE, RHODE ISLAND, ASSIGNOR TO AETNA AUTOMATIC OIL BURNER, INCORPORATED, OF NEW YORK, N. Y., A CORPORATION OF NEW YORK.

LIQUID-FUEL-FEEDING DEVICE FOR ROTARY OIL BURNERS.

Application filed August 20, 1923. Serial No. 658,444.

To all whom it may concern:

Be it known that I, JOHN SCHEMINGER, Jr., a citizen of the United States, residing at Providence, in the county of Providence and State of Rhode Island, have invented certain new and useful Improvements in Liquid-Fuel-Feeding Devices for Rotary Oil Burners; and I do hereby declare the following to be a full, clear, and exact description of the invention, such as will enable others skilled in the art to which it appertains to make and use the same.

This invention relates to devices for feeding liquid fuel to rotary oil burners, or the like, and more particularly to devices of the character referred to in which the liquid fuel supply tank is located above the level of the burner.

In the operation of pump-fed rotary oil burners, when the liquid fuel is conducted direct from the pump to the burner, the agitation or pulsatory action produced by the pump piston on the moving column of liquid seriously interferes with the operation of the burner, resulting at times in extinguishing the flame.

The primary object of my invention is to overcome this difficulty and provide simple, inexpensive, reliable and efficient means for effecting a steady and uniform feed or flow of the liquid fuel from a pump to the burner, or other device with which my invention may be used, unaffected by the pulsations of the pump as in pump-fed liquid fuel burners as heretofore ordinarily constructed, such means including a separating and quieting apparatus whereby a portion of the liquid in its passage from the pump to the burner is separated from the major portion and caused to descend and flow quietly to the burner unaffected by the agitation or pulsations produced by the pump piston, while the larger portion is returned to the supply tank or source from which it came.

A further object is to provide simple and efficient means to prevent the tank from being emptied by siphonic action, which is sometimes set up when the pump is stopped, and in case of leakage in the pipe line.

The invention will first be hereinafter more particularly described, with reference to the accompanying drawings, which are to be taken as a part of this specification,

and then pointed out in the claims at the end of the description.

In said drawings,

Fig. 1 is a side elevation, partly in section, of an apparatus embodying my invention, including a fuel supply tank, a pump, a liquid fuel separating and quieting apparatus, and pipe-connections between the same, and a fuel feed pipe leading from said apparatus to a burner or other device (not shown).

Fig. 2 is a vertical sectional view of the separating and quieting apparatus; and

Fig. 3 is a plan view of said apparatus, the top thereof being removed.

Referring to said drawings, in which the same reference characters are used to denote corresponding parts in different views, the letter A denotes a liquid fuel separating and quieting apparatus interposed in the pipe line between a supply tank L and a pump P; said tank being elevated above the level of a rotary oil burner or other device (not shown) with which the apparatus is used. The tank L is connected with the pump P by means of a suction pipe B, preferably through a priming chamber C, such as shown, for example, in my Patent No. 1,442,787 dated January 16, 1923, but such priming chamber may be dispensed with.

The separating and quieting apparatus is provided with a surplus liquid chamber A¹ and an auxiliary chamber A²; the chamber A¹ having a partition a¹ therein which terminates a suitable distance below the top of said chamber for the purpose hereinafter described, while the chamber A² is provided with a partition a² which terminates near the top or cover-plate a³ of the auxiliary chamber. The auxiliary chamber at one side of the partition a² is connected by a pipe D with the outlet or discharge from the pump P, and at the other side of said partition a fuel feed pipe E leads to the burner, said pipe E having a valve e therein for regulating the supply of fuel to the burner. A return pipe F, one end of which protrudes through the top of the supply tank L, extends from the larger chamber A¹ of the separating and quieting device, at one side of the partition a¹ therein, to said tank for returning the major portion of the liquid passing through said chamber to said supply tank. On the other side of the partition

^{a¹} there is a pipe section G leading from said chamber into the suction pipe B; the end of the pipe section which enters the bottom of the chamber having an inverted ⁵ cup-like cap g thereon which has a vent opening g¹ therein for a purpose hereinafter described. The top a³ of the auxiliary chamber A² is removably secured by means of set screws a⁴, or other suitable fastening ¹⁰ means, and has an opening therethrough in which is slidably fitted a lift valve H beside a depending partition a⁵ arranged about midway between the inner wall of the auxiliary chamber and the partition a². The top ¹⁵ a³ is also formed or provided with an opening at one side of the lift valve to receive a strainer I, which preferably has an exteriorly threaded part at its upper end screwed into said opening; said strainer ²⁰ having a hole in its bottom through which protrudes a nipple h at one end of a pipe section K, projecting from a valve casing M arranged in the auxiliary chamber; said valve casing having on the under side thereof ²⁵ of a tubular boss m which is interiorly threaded and screwed upon a reduced and threaded end of the fuel feed pipe E, the adjacent portion of which, below the bottom of the chamber, is threaded to receive ³⁰ a lock nut for securing it to said bottom. The valve chamber M is provided with a suitable stuffing box through which the stem h of the valve H passes into said chamber and rests upon a valve seat arranged directly over the outlet end of the fuel feed ³⁵ pipe E, for discharging a portion of the fuel entering the separator into the pipe E through which it is conducted to the burner, or other device, by gravity, so that sufficient ⁴⁰ pressure is maintained at the delivery end of said pipe to effect a steady and uniform supply of fuel to the burner.

In operation, the liquid entering the auxiliary chamber or compartment A², through the ⁴⁵ pipe D, rises in the space between the partition a² and the outer wall of the auxiliary chamber and flows over said partition into the space at the other side thereof, filling the latter space and the strainer therein, and ⁵⁰ raising the valve H, and with it the valve h¹, and the liquid which enters the strainer will escape through the valve h¹ and pass to the burner while the larger portion passes through the valve H into the compartment ⁵⁵ A¹ and from thence to the tank L. The body of the valve H fits loosely in the opening through the top plate a³ and has a head portion or flange h² thereon which seats snugly upon the top plate by gravity when the pump ⁶⁰ is stopped and the fluid pressure in the separating device is reduced. As the oil entering the auxiliary chamber passes over the top of the partition a² therein and into the space on the other side of said partition and out ⁶⁵ through the valve H, it is broken up suf-

ficiently to cause a separation of the globules of air contained therein and the smaller portion of the liquid fuel is thereby condensed and caused to pass to the burner under the pressure of gravity and the fluid pressure ⁷⁰ created by the pump, so that the liquid fuel passes quietly and evenly to the burner in a non-turbulent and steadily flowing stream, while the major portion is caused to ascend high enough to create back pressure ⁷⁵ opposed to and tending to counteract the pressure of the pump, whereby the desired separation and quieting of the minor portion of the liquid is effected, and such back pressure acting on the lesser portion effects the ⁸⁰ passage thereof quietly, continuously and evenly to the burner or other device with which the apparatus is used, unaffected by the pulsations or irregular movements of the pump piston or pistons. ⁸⁵

In the event of leakage in the pipe line when the pump is stopped and the burner extinguished, siphonic action may be set up and the contents of the supply tank emptied, with consequent loss and danger to the premises in which the apparatus is used, and to prevent this the vent overlying the pipe connection with the suction pipe is provided, so that when the liquid in the compartment A¹, or that part of said compartment between the partition a¹ and the inner wall of the compartment falls below the vent g¹, air will be admitted through said vent opening and caused to enter the suction pipe, thus ⁹⁰ breaking the siphon. ⁹⁵

It will be understood of course that the invention is not restricted in its application to rotary oil burners, but may be used for feeding liquid fuel generally to any device with which it is desired to use the same, and the ¹⁰⁰ appended claims should be read with this understanding. ¹⁰⁵

Having thus described my invention, what I claim as new and desire to secure by Letters Patent of the United States is:—

1. In combination with a liquid fuel supply tank, a pump, and a separating device, a suction pipe connecting said pump with said tank, a return pipe connecting said pump with said separating device, a surplus fuel return pipe connecting said separating device with said tank, and a fuel feed pipe connecting said separating device with a burner or the like; said separating device comprising a receptacle having a main and an auxiliary liquid chamber therein, the latter having a top-plate or cover and provided with a receiving chamber at one side and a separating chamber on the other side thereof, and means in said separating chamber whereby a part of the liquid drawn from said tank is fed to a burner or other device while the larger portion is returned to the tank; said means comprising a lift valve slidably fitted in an opening through the top of the separating ¹¹⁵ ¹²⁰ ¹²⁵ ¹³⁰

chamber and adapted to be opened by fluid pressure, an outlet valve of smaller capacity than said lift valve arranged below said opening and controlling the admission of
 5 fuel to said feed pipe, a strainer suspended in said separating chamber, and a pipe leading from said strainer to said feed pipe; said outlet valve being movable with and controlled by said lift valve for opening and
 10 closing the outlet through said feed pipe when said lift valve is raised and lowered.

2. In combination with a liquid fuel supply tank, a pump, and a separating device, a suction pipe connecting said tank with said
 15 pump, a return pipe connecting said pump with said separating device, a surplus fuel return pipe connecting said separating device with said tank and a fuel feed pipe connecting said separating device with a burner
 20 or the like; said separating device comprising a receptacle having a main and an auxiliary liquid chamber each having a partition therein to provide a liquid chamber of reduced size on each side of each partition,
 25 the auxiliary chamber having a top-plate or cover with a strainer suspended therefrom, a fluid pressure actuated lift valve slidably fitted in an opening through said cover, a valve chamber below said opening
 30 in communication with the fuel feed pipe, a tube projecting from said valve chamber into said strainer, and an outlet valve of less capacity than said lift valve seated in said valve chamber and movable with and controlled by said lift valve, for opening the outlet through said feed pipe when said lift valve is raised.

3. In combination with a liquid fuel supply tank, a pump, and a separating device, a suction pipe connecting said tank with said pump, a return pipe connecting said pump with said separating device, a surplus fuel return pipe connecting said separating device with said tank and a fuel feed pipe connecting said separating device with a burner or the like; said separating device comprising a receptacle having a main and an auxiliary liquid chamber each having a partition therein to provide a liquid chamber of reduced size on each side of each partition, the auxiliary chamber having a top-plate or cover with a strainer suspended therefrom, a fluid pressure actuated lift valve slidably fitted in an opening through said cover, a valve chamber below said opening in communication with the fuel feed pipe, a tube projecting from said valve chamber into said strainer, and an outlet valve of less capacity than said lift valve seated in said valve chamber and movable with and controlled by said lift valve, for opening the outlet through said feed pipe when said lift valve is raised; said return pipe entering said auxiliary chamber on one side of the partition therein and said fuel

feed pipe leading from said chamber on the other side of said partition, and said surplus fuel return pipe leading from said main liquid chamber at one side of the partition therein, and a pipe connection at the other side of said partition leading into said suction pipe and provided with means whereby air is admitted to the suction pipe when the liquid in said main chamber falls below a predetermined point, so as to prevent the tank from being emptied by siphon action.

4. An apparatus of the character described comprising a liquid fuel supply tank, a pump, a separating device, and suitable pipe connections between said pump and tank and between said separating device and said pump and said tank and a burner or the like, through which pipe connections liquid fuel may be drawn from said tank and fed in part to a burner or other device and the remaining portion returned to the tank; said separating device comprising a receptacle having a main and an auxiliary liquid chamber therein, the latter chamber having a removable top-plate or cover and partitioned to provide at one side a receiving chamber and at the other side a separating chamber, said separating chamber containing a fluid-pressure actuated lift valve slidably fitted in an opening through said cover, an outlet valve of less capacity than said lift valve protruding into a valve chamber arranged below said opening and controlling the outlet into the fuel feed pipe, a strainer in the upper part of the separating chamber, and a discharge pipe projecting from said valve chamber into said strainer; said outlet valve being movable with and controlled by said lift valve for opening the outlet through said feed pipe when said lift valve is raised.

5. In combination with a rotary oil burner, a liquid fuel supply tank located above the burner, a separating device located above said tank, a pump, pipe connections between said pump and tank and between said separating device and pump and tank and the burner through which a part of the liquid drawn from said tank is fed to the burner and the remaining portion returned to the tank; said separating device comprising a receptacle having a main and an auxiliary liquid chamber, the latter having a top-plate or cover and a partition therein to provide a receiving chamber at one side and a separating chamber on the other side of said partition, said main chamber also having a partition therein to provide a liquid chamber of reduced size on each side of its partition; said separating chamber having a strainer therein and a fluid-pressure-actuated lift valve slidably fitted in an opening through its top, a valve chamber arranged below said opening in communication with the fuel feed pipe and having a tubular projection protruding into said strainer, an outlet valve in

said valve chamber of less capacity than said lift valve controlling the outlet through said feed pipe and movable with said lift valve for opening said outlet when said lift valve is raised; the fluid return pipe entering said auxiliary chamber on one side of the partition therein and the fuel feed pipe leading from said chamber on the other side of said partition, and the surplus fuel return pipe leading from said main chamber on one side of the partition therein, and a pipe-connection on the other side of said partition leading into the suction pipe and provided with means for admitting air to the suction pipe when the liquid in said main chamber falls below a predetermined point, so as to prevent the tank from being emptied by siphonic action.

6. A liquid fuel feeding apparatus comprising a supply tank, a pump, a separating device and pipes connecting said pump and tank and said separating device with said pump and tank and with a burner, through which pipes a part of the fuel drawn from the pump is returned to the tank and another part fed to the burner; said separating device comprising a receptacle having a main and an auxiliary liquid chamber each having a removable cover and a partition therein so as to provide liquid chambers on opposite sides of each partition, a suction pipe connecting said tank with the inlet to said pump, a surplus fuel return pipe leading from said main chamber at one side of the partition therein into said tank, a pipe-connection between said suction pipe and said main chamber, on the other side of the partition therein, provided with a vent opening for admitting air to said suction pipe when the liquid in the chamber with which it connects falls below a predetermined point, a fuel return pipe connecting said pump with the auxiliary chamber of said separating device at one side of the partition therein, a fuel feed pipe leading from the other side of said partition to a burner or other device, and separating means in said auxiliary chamber whereby liquid fuel entering said auxiliary chamber is caused to pass through said lift valve 50 into said main chamber and thence to the tank while a smaller portion is caused to pass through said strainer and said valve chamber into said feed pipe for delivery to the burner; said separating means comprising a lift valve slidably fitted in an opening in the top of said auxiliary chamber, a valve chamber below said opening having a valve therein of less capacity than said lift valve and movable therewith, for closing the outlet to said feed pipe, a strainer in said auxiliary chamber, and a pipe leading from said strainer into said valve chamber.

7. In combination with a liquid fuel supply tank, a pump, and a separating device, a suction pipe connecting said tank with said pump, a return pipe connecting said pump with said separating device, a surplus fuel return pipe connecting said separating device with said tank and a fuel feed pipe connecting said separating device with a burner or the like; said separating device comprising a receptacle having a main and an auxiliary liquid chamber each having a partition therein to provide a liquid chamber of reduced size on each side of each partition, the auxiliary chamber having a top-plate or cover provided with an opening therein, a fluid pressure actuated lift valve 65 slidably fitted in said opening, a valve chamber below said opening in communication with the fuel feed pipe and with the liquid chamber in which it is placed, and an outlet valve of less capacity than said lift valve seated in said valve chamber and movable with and controlled by said lift valve, for opening the outlet through said feed pipe when said lift valve is raised.

8. In testimony whereof I affix my signature in the presence of two witnesses.

JOHN SCHEMINGER, JR.
